METHOD OF AND APPARATUS FOR WITHDRAWING LOWERMOST SHEETS FROM STACKS

Vincent E. Heywood and George A. Anderson,
Worcester, Mass., assignors to United States
Envelope Company, Springfield, Mass., a cor-
poration of Maine

Application March 12, 1940, Serial No. 323,514

4 Claims. (Cl. 271--1)

The present invention relates to an improved method of and apparatus for accomplishing the separate withdrawal of the lowermost sheet from a stack of flat sheets or blanks, such as is frequently employed in connection with envelope machines, or other mechanisms for the performance of various operations on a sheet.

When the lowermost sheet is withdrawn from a stack, certain difficulties arise, owing to the fact that the weight of the entire stack bears on the sheet being withdrawn, and thus creates a friction between sheets tending to cause the simultaneous withdrawal of more than one sheet. This tendency for sheets to adhere to each other is still further increased when the sheets being handled are composed of paper having a rough finish.

In order to overcome the effect of friction between the lowermost sheet and the remainder of the stack lying above it, it has heretofore been proposed to blow air under pressure at one or more places beneath the stack, to free the lowermost sheet by vibrating the same, as disclosed in Patent No. 1,942,527, issued January 9, 1934. While the aforementioned use of air pressure in facilitating the withdrawal of a lowermost sheet is effective when the sheets are composed of relatively thin smooth surfaced material, the desired results cannot be obtained when the stack is composed of very rough finished sheets, due to the inability of air pressure alone to overcome the tendency for the sheets to adhere to each other. Furthermore, when the stack is composed of punctured sheets, such as are employed in the manufacture of window envelopes, air under pressure is entirely ineffective, since it will blow through the stack.

According to the present invention, there is provided an improved method of and apparatus for withdrawing the lowermost sheet from a stack, characterized by the positive separation of the lowermost sheet from the stack at both its leading and trailing edges, preparatory to withdrawal. Furthermore, the actual withdrawal of the lowermost sheet is accompanied by the operation of means for positively holding the second lowermost sheet against withdrawal, thereby eliminating any possibility of the previously separated sheet pulling another sheet with it as it is withdrawn. The above and other advantageous features of the invention will hereinafter more fully appear from the following description, considered in connection with the accompanying drawing, in which:

Fig. 1 is a plan view of sheet-withdrawing apparatus embodying the invention.

Fig. 2 is a vertical sectional view along the line 2--2 of Fig. 1.

Figs. 3 and 4 are sectional views similar to Fig. 2, illustrating the steps in the separation and withdrawal of the lowermost sheet.

Fig. 5 is a fragmentary plan view of the sheet-gripping device.

In the illustrative embodiment of the invention shown in the drawing, the sheet-withdrawing apparatus is shown in connection with a stack of sheets 1 supported on an inclined stack plate 2, in cooperation with stops 3, although a horizontal stack plate may be used, if desired. While the sheets 1 are shown in Fig. 1 as being in the form of envelope blanks having window openings at 1a, obviously, the sheet-withdrawing apparatus, hereinafter described, may be also used in connection with sheets or blanks for other purposes.

A portion of the stack of sheets 1 projects beyond the upper edge of the stack plate 2, so that the under side of the lowermost sheet 1 can be engaged by a sucker 4 turnable about a hollow shaft 5, adapted to be connected at predetermined intervals to a suitable source of suction, not shown. In operation, the sucker 4 is adapted to engage and grip the under side of the lowermost sheet adjacent to its leading edge and to bend it over a roll 6 into a position in which it will be engaged by rotating segments 7 of frictional material, mounted on a shaft 8. The initial separation of the leading edge of the lowermost sheet is indicated in Fig. 3, and it is apparent that further rotation of the segments 7 from the position shown, will cause the sheet to be positively gripped between the segments 7 and roll 6, to effect complete withdrawal of the sheet from the stack, and its movement away from the stack for further operations thereon, as indicated in Fig. 4.

A portion of the stack also extends beyond the lower edge of the stack plate 2, so that the under side of the lowermost sheet 1 can be operated upon by a second sucker 9, turnable about a hollow shaft 10 to engage the lowermost sheet adjacent to its trailing edge. The shaft 10 is adapted to be connected at predetermined intervals to a suitable source of suction, not shown, and is operated in timed relation with the first shaft 5, so that the suckers 4 and 9 are adapted to simultaneously engage and grip the lowermost sheet adjacent both its leading and trailing edges. Therefore, as the leading edge of the lowermost

sheet is separated from the stack by the sucker 4, its trailing edge is also separated from the stack by the sucker 9, as shown in Fig. 3, so that the lowermost sheet is positively separated from the stack at opposite ends, in advance of its withdrawal movement by the segments 7.

That portion of the stack adjacent to the sucker 9 is also operated upon by a gripper 11 pivotally mounted on a shaft 12. As best shown in Fig. 5, the gripper 11 is forked, so as to provide pins 13 on opposite sides of the sucker 9, adapted to engage the extreme end of the stack, without interference with the sucker 9. Turning movement of the gripper shaft 12 is so timed that as soon as the sucker 9 separates the trailing edge of the lowermost sheet from the stack, by flexing it past the pins 13, the gripper is turned into the position of Fig. 3, to engage the pins with the stack. This turning movement of the gripper 11 is sufficient to slightly lift the end of the stack away from the plate 2, as indicated on an exaggerated scale, so that the pins 13 are very positively engaged with the end of the sheet next above the lowermost sheet that has already been separated from the stack, preparatory to its withdrawal.

With the parts occupying the position of Fig. 3, it is obvious then that continued rotation of the segments 7 from the position shown, will result in seizure of the leading edge of the lowermost sheet between the segments 7 and roll 6 and its withdrawal from the stack, as indicated in Fig. 4, at which time suction is removed from the suckers 4 and 9. Since the sheet next above the sheet being withdrawn is then positively held by the gripper pins 13, it is obvious that the withdrawal of the lowermost sheet is accomplished without any possibility of the sheet next above being withdrawn simultaneously. This result must necessarily follow, due to the simultaneous separation of both the leading and trailing edges of the lowermost sheet from the stack, and the positive engagement of the sheet next above by the gripper, in advance of the actual movement of withdrawal by the segments 7. Therefore, even though the sheets have such a rough finish as to exhibit a strong tendency to adhere to each other, this frictional engagement is broken and entirely overcome, due to the fact that by the time the lowermost sheet starts its withdrawal movement, the sheet next above has already been separated therefrom at opposite ends, and in addition, has been positively locked by the gripper against movement with the lowermost sheet.

From the foregoing, it is apparent that by the present invention there is provided an improved method of and apparatus for accomplishing the

5 separate withdrawal of the lowermost sheet from a stack of flat sheets or blanks, without possibility of the sheet next above being simultaneously withdrawn, even when the sheets are composed of material having a rough surface such as to cause a natural adhesion between the sheets.

We claim:

1. A method of withdrawing the lowermost sheet from a stack of flat sheets, characterized by the positive separation of the lowermost sheet from the stack at both its leading and trailing edges, preparatory to withdrawal of the separated sheet, followed by positive engagement of the next lowermost sheet to prevent its movement in the stack during withdrawal of the previously separated lowermost sheet.

2. Apparatus for withdrawing the lowermost sheet from a stack of flat flexible sheets comprising a supporting member for the stack, suction-operated elements for engaging and deflecting opposite edges of the lowermost sheet away from the stack beyond the ends of the supporting member, withdrawing means operable upon a deflected edge of the lowermost sheet, and gripping means engageable with the next lowermost sheet, in advance of the operation of said withdrawing means, to hold it positively against the remainder of the stack during the operation of said withdrawing means.

3. Apparatus for withdrawing the lowermost sheet from a stack of flat flexible sheets comprising a supporting member for the stack, pivotally mounted suckers engageable with opposite edges of the lowermost sheet which extend beyond said supporting member to flex said sheet away from the stack, withdrawing means engageable with a deflected portion of the lowermost sheet and a pivotally mounted gripper engageable with the next lowermost sheet, in advance of the operation of said withdrawing means, to hold it positively against the remainder of the stack during operation of said withdrawing means on the lowermost sheet.

4. Apparatus for withdrawing the lowermost piece from a stack of pieces comprising a supporting member for the stack, withdrawing means, means for positively separating the lowermost piece from the stack beyond opposite ends of said member in advance of operation of said withdrawing means on the separated piece, and means operable between a portion of the separated piece and the stack for positively engaging and holding the next lowermost piece against the stack to prevent movement of this piece during operation of said withdrawing means.
